United States Patent Office

JOHN W. HOIT, OF LEBANON, ILLINOIS.

Letters Patent No. 93,886, dated August 17, 1869.

IMPROVEMENT IN WASH-BOILERS.

The Schedule referred to in these Letters Patent and making part of the same.

To all whom it may concern:

Be it known that I, JOHN W. HOIT, of Lebanon, in the county of St. Clair, and State of Illinois, have made certain new and useful Improvements in Wash-Boilers; and I do hereby declare the following to be a full and true description thereof, reference being had to the accompanying drawings, and to the letters of reference marked thereon.

This invention relates to boilers and vessels in ordinary use for drenching and washing clothes and like materials; and

The nature of this invention is in the arrangement and conformation of the diaphragm under which the heated fluid gathers, and which serves also as a support to the materials being washed, and as a guide to the descending currents of fluid.

Said nature is also in the arrangement of the rising tubes for carrying up the ascending hot column of fluid, and in their construction for distributing and dispersing the discharging volume from said tubes.

To enable those herein skilled, to make and use my said improvements, I will now more fully describe the same, referring to the accompanying

Figure 1 as a sectional elevation longitudinally; to

Figure 2 as a transverse section; to

Figure 3 as a plan; and

Figure 4 as a sectional view of the discharging-nozzle, hereinafter more fully described.

I construct the boiler A of any usual material and form.

Within said boiler, and resting upon the bottom thereof, I place the diaphragm B, of a rounding form, as indicated in fig. 2.

Between said diaphragm and the bottom of the boiler, there is thus formed a chamber, B', which, by its close proximity to the heated bottom, to which the heat-source is usually contiguous, is intensely heated, and there is thus created a tendency of upward flow from said chamber B' of the fluid therein.

To allow the heated fluid, which is usually water, to rise, I arrange the tubes C, their influx-openings being close to the bottom of the boiler, and being turned toward the middle of the same, as indicated in fig. 1.

Said tubes C are properly supported upon the bottom and sides of the boiler, and rise up to the discharging-heads D, from which the fluid is dispersed over the clothes usually placed within the boiler A.

The expansion of the fluid in the lower part of the boiler, and especially in the chamber B', thus creates a flow of the fluid to the tubes aforesaid, and an ascension in the same.

In order that the less heated fluid, in its descent shall not check or reduce the force of the rising currents, it is advisable to localize each of said currents.

The colder fluid passes down near the side surface, of the vessel A, and to enable the same readily to enter under the diaphragm B, this is arranged with perforations b, and the wire or other guard-frame, b', the latter preventing clothes from choking or covering the perforations b.

Again, to prevent the colder current from contact and check upon the ascending flow, the influx-orifices of the tubes C were turned, and run toward the middle of the boiler, as above indicated.

But, lastly, to prevent the descending flow to interfere with the rising one, and especially to prevent the rising flow in the tubes C from being chilled by the descending fluid, I arrange the side-plates E immediately in the rear of the tubes C, and secured to the sides of the boiler A. Said plates prevent the descent of the colder fluid along the tubes C, and at the same time form chambers E', these being open at the bottom, and receiving steam and highly-heated fluid from the lower parts of the boiler, and forming in this wise an additional heating-chamber acting upon the tubes C and the fluid therein.

The discharging-heads D are formed of a central part, D¹, and the spouts D². Said spouts are bent in any required form, and in order that the outflowing water may be directed to any required point, I arrange the same adjustably as follows:

The spouts D² fit about the pipes d, and may be turned about the same by the handle d¹.

In order to prevent disconnection, a groove, d², is formed in the pipes d, and a prong of the handle d¹ engages therein.

For further distributing the outflowing fluid column, I arrange the discharge-orifice e in the central head D¹, and the orifices e' in the spouts D², there being such a number thereof as may be deemed expedient.

Having thus fully described my said invention,

What I claim, is—

1. The arrangement of the vessel A, having a rounded diaphragm, B, with perforations b therein, and raised guards b' thereon, and combined with the tubes C, substantially as set forth.

2. The side-plates E, arranged to form the heating-chambers E', and combined with the tubes C, substantially as and for the purpose set forth.

In testimony of which, I have hereunto set my hand, in the presence of witnesses.

JOHN W. HOIT.
